[57] ABSTRACT

An improved security sealing device comprises a pair of hingedly connected metal jaws of which one has a tongue insertable through a slot in the other. The slot has inward facing lips while the tongue has catch tabs which, after insertion of the tongue through the slot, move to positions on opposite sides of the tongue such that by engagement with the lips of the slot they thereafter prevent opening movement of the jaws. By this arrangement it is virtually impossible to manipulate the jaw locking parts without visibly damaging the sealing device.

SECURITY SEALING DEVICE

This invention is an improved security sealing device which is intended to be applied manually to a tie cord or other package binding means as a deterrent to unauthorized interference.

More especially the security sealing device is of a kind comprising a pair of hinged jaws which by application of finger pressure can be closed on to the binding means so as to become locked together.

The underlying intention of these seals is that once the jaws have closed they cannot be released from the binding means without manifest damage or fracture of the device. An ideal sealing device is one which cannot be accidentally damaged, yet readily fractures or becomes obviously deformed by unauthorized interference and which maintains a tight grip on the binding means such as will prevent the latter from being pulled through the jaws.

In certain known forms of security sealing device of the kind referred to, these criteria are not fulfilled. For instance it is sometimes possible by insertion of a thin tool to cause retraction or disengagement of its locking parts to enable the device to be removed or loosened, it furthermore being possible to restore the locking parts to their original positions without fracture or damage. Unauthorized interference with the sealing device, the binding means or the package itself may thus fail to be detected.

The intention of the present invention is to provide an improved security sealing device in which it is virtually impossible to manipulate the jaw locking parts without visibly damaging the sealing device.

In accordance with the present invention a security sealing device comprises a pair of metal jaws hinged together at one end, one of the jaws having a tongue which is insertable through a slot formed in the other jaw, and is characterized in that the slot is provided with inward facing lips whilst the tongue has catch tabs which after insertion of the tongue through the slot move to positions on opposite sides of the tongue such that by engagement with the lips of the slot they thereafter prevent opening movement of the jaws.

Preferably the movement of the catch tabs to their operative positions is induced by bending of the tabs which occurs when the tip of the tongue presses against the inside surface of the opposing jaw.

Preferably also there are three catch tabs cut away from the tongue and situated one at the tip and the other two at the respective sides of the tongue.

One particular and at present preferred form of security sealing device in accordance with the present invention is hereinafter described by way of example with reference to the accompanying drawings, in which:

FIG. 1 is a plan view showing the sealing device in a fully open position;

FIG. 2 is a side elevation of the sealing device in its fully closed position;

FIG. 3 is a fragmentary sectional elevation similar to FIG. 2;

FIG. 4 is a plan view of the sealing device in a fully closed position wherein it is sealing a wire or cord; whilst

FIG. 5 is a perspective view of a modified form of the sealing device shown in FIGS. 1 to 4.

Referring now to the drawings, it can be seen that the sealing device comprises a pair of flat thin metal jaws 1, 2 one slightly smaller than the other, foldably connected at one end, each jaw having a skirting flange 3 along its side and front edges. Adjacent the fold, or hinge, the skirting flanges 3 are cut away to provide openings for admitting a tie cord 4 (FIG. 4) or other binding means to pass through the jaws 1, 2 so as to be pinched or seized between them when the jaws 1, 2 are closed and become locked to one another as hereinafter described.

At the free end of the smaller jaw 2, a tongue 5 extends substantially perpendicularly from it whilst the free end of the other jaw 1 has a protective housing comprising a flat top piece 6 and depending side lugs 7. The top piece 6 is pierced by a laterally extending slot 12 having opposed lips 8 which project internally of the housing towards the inside facing surface of the jaw.

20 The tongue 5 on the jaw 1 is cut so as to define three catch parts or tabs 9, 10. A central one 9 of these tabs is of triangular shape and situated adjacent the tip of the tongue 5 whilst the other tabs 10 are of elongated shape and situated at the respective side edges of the tongue 5.

25 The hinge or fold line 13 between the jaws 1 and 2 constitutes a line of weakness which would be liable to fracture if the closed sealing device should be tampered with.

30 The security sealing device is also provided with some means by which the tie cord 4 or other binding means may be positively anchored or attached to it. This means could have the form of an apertured tab 11 as shown in FIGS. 3 and 4 which projects laterally inwards from the skirting flange 3 of the smaller jaw 2 and to which the cord or other binding means would be knotted or otherwise attached.

35 Alternatively the device might be formed as shown in FIG. 5 with appropriately sized and shaped holes 14 in the vicinity of the hinge or fold line 13 for the same purpose. There would then be no need to cut away the skirting flanges 3 in the vicinity of the hinge.

40 The security sealing device is operated by closing the jaws 1, 2 towards one another using finger pressure so as to seize the tie cord 4 or other binding means therebetween. When the jaws are closed on to one another the tongue 5 on the jaw 2 enters the slot in the housing of the other jaw 1. When the tip of the tongue 5 engages the inside surface of the other jaw 1, the tongue is deformed into a curved shape and this deformation results in a splaying out of the catch tabs 9, 10. Thus the central catch tab 9 splay out beneath the foremost lip 8 of the slot in the lower jaw, whilst the two side catch tabs 10 splay out behind the rearmost lip 8 of that slot.

45 Since the skirt flanges 3 of the jaw 1 closely overlap the skirt flanges of the jaw 2 and due to the existence of the protective housing, it is virtually impossible by use of any instrument to gain access to the catch tabs 9, 10 for the purpose of restoring them to their undeformed positions such as would enable the jaws 1, 2 to be even partly reopened. Any attempt to reopen the jaws in any other way inevitably must result in fracture at the fold line or damage to the sides of the jaws or the catch tabs, all of such damage being then readily apparent.

As an additional aid to security, authorized users of security sealing devices as above described would be provided with an embossing or other tool for forming or marking a monogram or other characteristic designation on one or other of the jaws.

The provision of three catch tabs, of which one is deformed in an opposite direction to the direction of deformation of the two others, which deformation occurs when the jaws are closed together is an important feature of the sealing device.

The facility of anchoring the binding medium is also important because it defeats attempts to extract the binding means and subsequently reinsert it after partial springing open or deformation of the jaws. With conventional sealing devices, this manoeuvre needs relatively little movement or distortion in the vicinity of the hinge, whereas when the binding means is anchored, the two jaws need to be opened right out even if opening without fracture at the hinge line was possible.

This is particularly significant when the binding means is wire.

When the sealing device includes anchoring means it is particularly suited to the sealing of single strand wire as opposed to multi-strand wire which due to its corrugated surface has hitherto necessarily been used with sealing devices which rely only upon co-acting means

which grip the wire.

We claim:

1. A device for the security sealing of a tie cord or other package binding means, comprising a single piece of thin sheet material having side flanges and which is foldable about a fold line to provide a pair of jaws, one of said jaws having at its free end an extension extending backward in the direction of said fold line, said extension having a slot formed therein with lips directed inwardly of the jaw from each side edge of the slot, the other of said jaws having at its free end a tongue which is insertable through said slot, said tongue having three catch tabs cut away in the plane of the tongue and situated one at the tip and the other two at the respective side edges of the tongue, the tip of said tongue being engageable with the inside of the jaw having the slot when the jaws are closed upon one another so that as a result of consequential bending of said tongue said catch tabs move to positions on opposite sides of the tongue such that by engagement with the lips of said slot they thereafter prevent opening movement of the jaws.
2. A security sealing device as claimed in claim 1 and having holes therein for allowing access of binding means to and from the interior of the closed jaws.
